UNITED STATES PATENT OFFICE

2,494,160

STRIPING TOOL

William A. Bihary, Miami, Fla.

Application December 29, 1945, Serial No. 637,881

1 Claim. (Cl. 33—27)

1

This invention relates to a striping tool and more particularly to a device for striping disc wheels.

The primary object of the invention is to produce concentric stripes on a wheel for decorative purposes.

Another object is to facilitate the production of stripes of varying widths as well as stripes of different diameters.

The above and other objects may be attained by employing this invention which embodies among its features a base adapted to be located by the hub cap receiving opening of the disc wheel and carrying an extensible arm which rotates about the axis of the base and concentric to the wheel, which arm also rocks about an axis perpendicular to the axis about which it rotates, a paint feeding unit carried by the arm and a narrow paint distributing wheel carried by the paint feeding unit.

Other features include means yielding to urge the arm to contract toward the axis about which it is mounted to rotate, and means to extend the arm against the urge of the contracting means whereby concentric stripes which may be varied in width as well as diameter may be produced on the outer surface of a wheel disc.

In the drawings:

Figure 1 is a top plan view of a striping tool embodying the features of this invention,

Figure 2 is a side view in elevation thereof.

Figure 3 is an enlarged longitudinal sectional view through the striping tool,

Figure 4 is a transverse sectional view taken substantially on the line 4—4 of Figure 3,

Figure 5 is a bottom plan view of the paint feeding unit and the distributing wheel,

Figure 6 is a side view in elevation thereof,

Figure 7 is an end view of Figure 6,

Figure 8 is a transverse sectional view taken substantially on the line 8—8 of Figure 5, and

Figure 9 is a transverse sectional view taken substantially on the line 9—9 of Figure 5.

Referring to the drawings in detail my improved wheel striping device comprises a base plate 15 provided on its underside with a concentric depending flange 16 which is of a size readily to fit within the hub cap receiving opening of a disc wheel. The collar or flange 16 is inwardly offset from the peripheral edge of the base 15 to form a shoulder 17 which serves to support the device in position on the wheel. As illustrated in Figure 2 the plate 15 is of generally convex construction and mounted axially thereof is an upstanding tubular sleeve or collar 18. 55

2

This collar is externally screw-threaded and is adapted to engage in an internally screw-threaded bore 20 formed in the base 15 and threaded on said collar 18 is a lock nut 21 so that the collar 18 may be adjustably secured to various heights with relation to the base 15.

Extending into the sleeve 18 is the cylindrical stem 22 of a yoke 23 in which a transversely extending pivot pin 24 is secured. This pivot pin forms a support for an ear 25 carried by an extensible arm designated generally 26 which as illustrated is adapted to rotate about the axis of the base 15 and to rock about the axis of the pin 24.

15 The extensible arm 26 comprises a tubular body 21 into one end of which is fitted an internally screw-threaded collar 28 while the opposite end of the sleeve carries a collar 29 having a smooth interior bore 30 through which a rod 31 enters the sleeve in telescopic relation therewith. Secured to the rod near its innermost end is an outstanding annular flange 32 and surrounding the rod between the flange 32 and the collar 29 is a compression coil spring 33 which yielding 20 urges the rod to telescope into the sleeve 27 as will be readily understood upon reference to Figure 3. As shown the innermost end of the rod bears against a longitudinally extending adjusting screw 34 which is threaded into the 25 threaded opening of the collar 28 and carries at its outer end a knurled head 35 by means of which the screw may be rotated to advance the rod 31 with relation to the sleeve 27 or to permit it to be retracted under the influence of the spring 33. Secured to the outer end of the rod 31 is an eye 36 into the bore 37 of which opens an internally screw threaded radial bore for the reception of a set screw 38 provided with a knurled head 39 by means of which the screw may be 30 adjusted into or out of the opening 37 for a purpose to be more fully hereinafter explained.

A paint feeding unit designated generally 40 comprises a body 41 formed with an internally screw threaded socket 42 into which the externally screw threaded neck of a paint container 43 is adapted to be received as will be readily understood upon reference to Figure 8. Fitted in the body 41 and leading through an opening 44 arranged axially thereof is a nipple 45 the outer portion of which is slotted as at 46 to form a pair of upwardly extending ears 47 which are pierced with aligned openings 48 for the reception of a pin 49 extending transversely with relation to the longitudinal axis of the 50 nipple 45 and serving as a support for a paint

distributing wheel 50 the periphery of which is knurled to provide peripheral paint distributing recesses. Extending radially from the socket 42 is a trunnion 51 which is of an external diameter snugly to fit the opening 37 in the eye 36 in order to support the paint feeding unit, the container and the paint distributing wheel in place on the arm 26 as illustrated in Figures 1 and 2. In order to compensate for the off set relationship between the axis of the arm 26 and the axis of the shaft 49 I have found it advantageous to incline the axis of the pin 49 with relation to the axis of the trunnion 51 in order to secure proper tracking of the paint distributing wheel on the article being striped.

In use, it will be understood that the base 15 is seated on the outer side of the wheel to be striped as illustrated in Figures 1 and 2 with the flange 17 engaging the wheel in the immediate vicinity of the opening through which the hub cap enters and the collar 16 seated in said opening. By thus locating the tool with relation to the wheel, the eye 36 may be rotated concentrically about the axis of the base 15 and when the parts are thus assembled and the paint feeding unit mounted in the eye 36 with the trunnion 51 extending through the opening 37 and locked therein by means of the set screw 38 it will be obvious that upon swinging the arm 26 about the axis of the base 15 paint flowing down through the opening in the nipple 45 will contact the knurled edge of the wheel 50 and be distributed thereby onto the outer surface of the disc wheel to be striped. By rotating the screw 34 it will be evident that the rod 31 may be moved outwardly against the compression of the spring 33 so that the striping may be in the form of a plurality of separate concentric circles or should a wider stripe be desired the screw 34 is adjusted to produce the first stripe after which it may be turned inwardly or outwardly so that upon a second revolution of the arm 26 about the axis of the base 15 the wheel 50 may be made to move concentrically with the first stripe in such a manner that the next

stripe being placed thereon will overlie or abut the edge of the first stripe to produce a stripe of greater width according to the desires of the user. Obviously stripes of various different widths may readily be achieved by manipulating the screw 34 to slide the eye 36 inwardly or outwardly with relation to the axis of the base 15.

What I claim is:

- 10 A wheel striping tool comprising a base, a circular flange depending from the base, said flange being adapted to be located in the hub cap receiving opening of a disc wheel, a tubular body mounted on the base to rotate about the axis of the flange and to rock about an axis which intersects and lies perpendicular to the axis about which it rotates, a rod telescopically entering one end of the tubular body, a paint feeding and distributing unit carried by the end of the rod remote from that which enters the sleeve, a compression spring surrounding the rod yieldingly to urge it to telescope into the sleeve and a screw threaded into the end of the sleeve remote from that entered by the rod for engaging the end of the rod to hold it against movement under the 20 effort of the spring.

WILLIAM A. BIHARY.
